UNITED STATES PATENT OFFICE.

JOHN C. SCHAEFER, OF NEW YORK, N. Y., ASSIGNOR TO THE SCHAEFER SAFETY VALVE COMPANY, OF SAME PLACE.

SAFETY-VALVE FOR BEER-CASKS.

SPECIFICATION forming part of Letters Patent No. 359,892, dated March 22, 1887.

Application filed August 19, 1886. Serial No. 211,231. (No model.)

To all whom it may concern:

Be it known that I, JOHN C. SCHAEFER, a citizen of the United States, residing at New York, in the county and State of New York, 5 have invented new and useful Improvements in Safety-Valves for Beer-Casks, &c., of which the following is a specification.

My invention relates to improvements in safety-valves for beer-casks; and it consists, essentially, in the combination, with a valve-shell, a lubricating cup or vessel, and a valve-seat therein, of a weighted valve-disk on said seat, a passage or passages leading from the valve-shell to the seat and opening below the valve-disk, and a passage leading from below the valve-disk to the lubricating-cup, the said valve-disk being constructed to permanently close the orifices of the passages in the valve-seat from the lubricant above the said seat; 15 and also in combination with the above-mentioned parts is a chamber containing a diaphragm, which prevents the lubricant from entering the cask, all of which is more fully pointed out in the following specification and 20 claims, and illustrated in the accompanying drawings, in which—

Figure 1 represents a longitudinal vertical section of the safety-valve. Fig. 2 is a transverse section thereof in the plane $x x$, Fig. 1. 30 Fig. 3 is a sectional plan or top view with the valve-disk and adjacent parts removed. Fig. 4 is an inverted plan view of a detail part.

Similar letters indicate corresponding parts.

In the drawings, the letter A designates the 35 valve-shell.

B is a cup or vessel containing the lubricant, such as water or oil, which communicates with the interior of the valve-shell through a passage, b.

C is a chamber that is in communication 40 with the valve-shell, the latter being secured to a branch, C', of the former. The chamber is also provided with a lateral branch, C'', having therein a stop-cock, D, for transmitting air into the beer-cask should undue pressure arise from the pump, which will occur if a chip gets before the racking-cock and prevents the stream of beer from flowing out.

A longitudinal branch, E, on the chamber 45 is partly screw-threaded to engage with the

threaded bush of the cask when the valve is applied. The chamber contains a longitudinal diaphragm, F, which emanates from below the branch C' and extends upwardly in the chamber up above the level of the upper edge 55 of the cup or vessel B. The lubricant from the cup or vessel completely fills the valve-shell and rises in the reservoir f, formed between the diaphragm F and the wall of the chamber to the level in the cup or vessel. 60

In the bottom of the cup or vessel is formed a seat, g, for a valve-disk, G, which latter consists of a circular flat piece of soft rubber or similar elastic material, which is held down to the seat at and near its periphery by an annular disk or bushing, H, which is screwed upon the same. The bushing is provided with a concave or recessed portion, which allows the central portion of the valve-disk to rise from its seat when under pressure. A washer, 70 h, can be inserted between the valve-disk and the bushing H. The valve-disk is held down on its seat by means of a piston, I, which extends through the bushing H, and the stem i of which is engaged by an arm, J, which carries an adjustable weight, J', Fig. 1. A cover, M, Fig. 1, provided with one or more holes or openings, m, and a long tubular shank, closes over the valve, the holes or openings in the cover allowing the lubricant to freely enter 80 the casing thus formed and come in contact with the upper surface of the valve-disk G therein. 75

Passages or channels a lead from the valve-shell A and open in the valve-seat, through 85 which passages the accumulating gases pass and act against the valve-disk. When in excess of pressure, the gases distend the valve-disk and make their exit underneath the same through an exit passage or channel, B', 90 which leads downward from the valve-seat and opens into the cup or vessel B.

The valve-disk G, whether distended or on its seat, prevents the egress of the gases through its casing, and also prevents at all 95 times the lubricant from entering the valve above the valve-seat.

It will be noticed that the lubricating liquid in the cup or vessel can moisten only the upper surface of the valve-disk through the holes 100

in the valve-cover M, and in order to insure a constant contact of the liquid with the bottom or lower surface of the disk I provide a gate, N, Fig. 1, for the opening b, leading to the valve-shell, which gate must close this opening while the valve is in use, but can be opened before the filling of the cask has begun. This gate consists of a shell, which screws into the bottom of the cup or vessel, and is provided with a series of transverse holes, n, which open the communication between cup and shell when they rise above the level of the bottom. A suitable seat is provided for the gate, and a stem, n', projecting from the shell, allows it to be easily turned.

In applying the valve to use, the cup or vessel is supplied with water, preferably, which flows through the passage b into the valve-shell and chamber, and also fills the valve-casing, whereby the liability of the valve to "gum" or "foul" is entirely obviated. The liquid is prevented from flowing into the cask by the diaphragm F.

The object of my invention is to produce a safety-valve for casks which is durable, efficient, and simple, and which can be manufactured cheaply. With the construction of valve specified the weight J' can be made very heavy, so as to prevent a constant escape of the generating-gases, which is liable to occur with ordinary valves when the existing pressure of gases is below that fixed by the weight.

What I claim as new, and desire to secure by Letters Patent, is—

1. The combination, with the valve shell, a lubricating cup or vessel, and a valve-seat therein, of passages leading from the valve-shell and the cup or vessel to the valve-seat and having orifices therein and a valve-disk over said seat constructed to permanently close the said orifices in the same from the

lubricant in the cup or vessel above the said valve-seat, substantially as shown and described.

2. The combination, with the valve-shell, the lubricating cup or vessel, and the valve-seat therein, of the weighted distensible valve-disk G on said seat, a passage or passages, a, leading from the valve-shell to the valve-seat and opening below the valve-disk, and a passage, B', leading from below the valve-disk to the lubricating cup or vessel, substantially as shown and described.

3. The combination, with the valve-shell and the lubricating cup or vessel having a valve-seat, of the weighted valve-disk G, the perforated cover M over said valve-disk, a passage, a, leading from the valve-shell to the valve seat and opening below the valve-disk, a passage, B', leading from below the valve-disk to the lubricating cup or vessel, a chamber, C, in communication with the valve-shell, and a diaphragm, F, in said chamber, extended upward from the valve-shell above the level of the lubricating cup or vessel, substantially as shown and described.

4. The combination, with the valve-shell, the lubricating cup or vessel, and the chamber and its diaphragm, of a valve-disk, a passage leading from the valve-shell to the lubricating cup or vessel and controlled by said valve, and the gate N, constructed to admit the lubricant in the cup or vessel to the valve-shell and chamber, substantially as shown and described.

In testimony whereof I have hereunto set my hand and seal in the presence of two subscribing witnesses:

JOHN C. SCHAEFER. [L. S.]
